US00D989200S

(12) **United States Design Patent** (10) **Patent No.:** **US D989,200 S**
(45) **Date of Patent:** ** *Jun. 13, 2023

(54) **EXERCISE DEVICE**

(71) Applicant: **My Chi Nguyen**, Brea, CA (US)

(72) Inventors: **Vien Quang Ly**, Ho Chi Minh (VN);
Kien Van Ngo, Ho Chi Minh (VN);
Vinh The Le, Ho Chi Minh (VN)

(*) Notice: This patent is subject to a terminal disclaimer.

(**) Term: **15 Years**

(21) Appl. No.: **29/738,029**

(22) Filed: **Jun. 14, 2020**
